L. K. SNELL,
SUPPLY AND EXHAUST MANIFOLD FOR INTERNAL COMBUSTION ENGINES,
APPLICATION FILED OCT. 1, 1917.

1,403,353.

Patented Jan. 10, 1922.

UNITED STATES PATENT OFFICE.

LYLE K. SNELL, OF DETROIT, MICHIGAN, ASSIGNEE TO CADILLAC MOTOR CAR COMPANY, OF DETROIT, MICHIGAN, A CORPORATION OF MICHIGAN.

SUPPLY AND EXHAUST MANIFOLD FOR INTERNAL-COMBUSTION ENGINES.

1,403,353.

Specification of Letters Patent. Patented Jan. 10, 1922.

Application filed October 1, 1917. Serial No. 194,261.

To all whom it may concern:

Be it known that I, LYLE K. SNELL, a citizen of the United States, and resident of Detroit, Wayne County, State of Michigan, have invented certain new and useful Improvements in Supply and Exhaust Manifolds for Internal-Combustion Engines, of which the following is a specification.

This invention relates to improvements in hydrocarbon motors.

One of the objects of this invention is to devise an efficient hydrocarbon motor of neat appearance and simple construction.

Another object of this invention is to provide an efficient heating device for the combustible gases as supplied to a hydrocarbon motor.

Another object of this invention is to provide an adequate control for the temperature of the combustible gases as supplied to a hydrocarbon motor immediately before entering the cylinders.

Another object of this invention is to devise a heating device and control for the combustible gases as supplied to a hydrocarbon motor which shall be readily removed for cleaning or replacement.

Another object of this invention is to devise a heating device for combustible gases as supplied to a hydrocarbon motor which shall be constant and dependable in operation.

These, and other objects, will more clearly appear from the following description taken in connection with the accompanying drawings which form a part of this specification and in which:

Figure 1 is an end elevation of a V type hydrocarbon motor, with substantially one half in section to more clearly show the invention.

Figure 2 is a longitudinal section on the line 2—2 in Figure 1.

Referring to the drawings, a hydrocarbon motor 10 of V type is shown having the blocks of cylinders 11 mounted in V relation one to the other on the crank case 12 and having the valves 13 covering the inlet and outlet ports as customary in motor construction of the type shown.

Each block of cylinders 11 has an intake manifold 14 cast integral therewith and extending along one side over the inlet ports 15, said ports 15 being branched each to two

cylinder valve chambers, though it must be understood that the ports 15 may be of any number or arrangement to suit the cylinder and valve mechanism.

The manifold 14 has an intake 14' midway of its length and a jacket casing 16 formed substantially two thirds around the manifold as shown in Figure 1, though it must be understood such an arrangement is not essential and the jacket at parts may be formed around all sides of the manifold. The jacket 16 extends the entire length of the manifold and has the end inlet and outlet openings 17 and 18 respectively, suitably threaded. The intake manifold at the end next to the outlet opening 18 in the jacket 16 has a threaded opening 19 and the enlarged end 20 forming a valve chamber for the valve 21, which is secured to the outer end of the thermostat rod 22, said rod extending into the thermostat 23, having one end anchored by threading the same into the opening 19 and extending to the opposite end of the intake manifold where it is supported in an orifice 24 in the boss 25. A spring 26 is placed between the valve 21 and a plug 27 bushing 28 screwed into the opening 18 in the exhaust jacket.

It will be noted that the thermostat extends the entire length of the intake manifold, past the inlet ports 15 and as the manifold is formed in the block with the cylinders and protected by the jacket casing 16, the temperature of the gases within the manifold will be the nearest approach to that within the cylinders in which it is possible to adequately arrange a control device. Thus the thermostat 23 is placed where the control thereof will be most effective and the gases after leaving the manifold will be subjected to a minimum degree of change.

It will be understood that the thermostat, when contracted, due to a low temperature, will permit the spring 26 to move the rod 22 and valve 21 inwardly, opening the space between the valve chamber 20 and the plug 28 bushing 27 and also when the thermostat becomes sufficiently heated the corrugated tube contained therein will be actuated, as well understood in the art, to force the rod 22 and valve 21 outwardly and close the opening about and through the plug bushing 27.

The jacket of the intake manifold 14 is heated by exhaust gases from the exhaust

manifold 28 secured along the side of each block of cylinders as by the bolts 29 and receiving the heated exhaust gases from the several cylinders through the ports 30.

5. The exhaust manifold 28 is formed with the closed end 31 with the nozzle 32 extending thereinto for some distance along said manifold, and the open or exhaust outlet end 33 with the V branch 34 formed adjacent thereto and on one side thereof. The V branch 34 is connected as by a pipe 35 with the inlet opening 17 in the intake manifold jacket and the outlet opening from said jacket formed through the plug bushing 27, 15 is connected as by a pipe 36 with the nozzle 32.

The connections between the exhaust manifold and the intake manifold jacket as above explained will always assure a supply of 20 heated gases passing about the intake manifold jacket, depending on the extent the valve 21 is opened and the valve being at the outlet end will always permit a certain amount of exhaust gases to be in the jacket 25 about the intake and prevent sudden fluctuations or changes in temperature.

As shown in Figure 1, the intake manifolds 14 have the intakes 14' thereof bridged by the induction pipe 37 of any desired form 30 though shown as inverted U shape and having the carburetor 38 secured to the central intake opening 39.

The induction pipe 37 is provided with a jacket casing 40 substantially throughout the 35 entire length thereof and connections are made for supplying the jacket 40 with exhaust gases as by the pipes 41 leading from the inlet ends of the manifold jackets to ports 42 (shown in dotted lines, Fig. 1.) and 40 pipes 43 connecting the upper part of the induction pipe jacket with the outlet ends of the intake manifold jacket. Thus a supply of exhaust gases is fed about the induction pipe to heat the same when needed and assist 45 in preparing the combustible gas passing therethrough for admission to the cylinders.

While I have described and will specifically claim what I deem to be a preferred embodiment of my invention, it will be 50 obvious to those skilled in the art that various modifications and changes may be made without departing from the spirit and scope hereof.

Having thus described my invention, what 55 I claim and desire to secure by Letters Patent is:

1. A hydrocarbon motor having a jacketed gas intake manifold, an exhaust manifold, an inlet pipe connected with said jacket and 60 opening to said exhaust manifold in a direction against the flow of gases therethrough, an outlet pipe connected with said jacket and opening directly into said exhaust manifold in the direction of the flow of gases 65 therethrough, and a valve located adjacent neeting said V branch and said nozzle inlet

the outlet end of said jacket and adapted to control the flow of exhaust gas therethrough.

2. A hydrocarbon motor having two blocks of cylinders arranged in V relation, 70 one to the other, each block having an intake manifold arranged along the inner side thereof and an exhaust manifold connected thereto, a jacketed induction pipe bridging said intake passages and thermostatically 75 controlled means for causing exhaust gases to flow from said exhaust manifold through said jacketed induction pipe and back to said exhaust manifold.

3. A hydrocarbon motor having two 80 blocks of cylinders arranged in V relation one to the other, each block having an intake manifold formed integral therewith and with an exhaust jacket casing surrounding the same, a pair of exhaust manifolds arranged along side said cylinders, a gas induction pipe bridging said intake manifolds and having an exhaust jacket casing surrounding the same and thermostatically controlled means for causing exhaust gases to 85 flow from said exhaust manifold throughout said exhaust jacket casings and return to said exhaust manifold.

4. A hydrocarbon motor having a plurality of cylinders cast en bloc with a gas intake 90 passage formed integral therewith and an exhaust gas manifold arranged therealong, a heating jacket associated with said intake passage and communicating with said exhaust manifold through permanently open 100 inlet and outlet connections, and means for causing exhaust gases to flow from said exhaust manifold through said connections and about said gas intake passage and back into said exhaust manifold.

5. A hydrocarbon motor having a plurality of cylinders cast en bloc with a gas intake 105 manifold passage formed integral therewith, and an exhaust gas jacket formed therealong having inlet and outlet ports, and a thermostat extending along said intake manifold passage and controlling one of said exhaust jacket openings.

6. A hydrocarbon motor having a plurality of cylinders cast en bloc with a gas intake 110 manifold passage formed integral therewith and extending over a plurality of gas intake ports and having inlet and outlet ports and a thermostat extending along said intake passage past the intake manifold ports and having a valve arranged at one end thereof and extending into said exhaust jacket and controlling the outlet port therefrom.

7. The combination with hydrocarbon 115 motor having a jacketed gas intake, of an exhaust manifold secured to said motor and having a nozzle inlet at one end thereof and a V branch at the opposite end thereof in the direction of said nozzle and means connecting said V branch and said nozzle inlet 120

with inlet and exhaust ports of said gas intake jacket.

8. A gas intake for hydrocarbon motors comprising a center gas passage, an exhaust jacket formed about said passage, a thermostat inserted in an end opening in said passage and extending throughout the length thereof, a bushing inserted in an end open-

ing in said exhaust jacket in alignment with said thermostat, a valve secured to said thermostat and closing the exhaust jacket about the bushing opening and a spring between said valve and said bushing.

In testimony whereof I affix my signature.

LYLE K. SNELL
